UNITED STATES PATENT OFFICE.

JAMES E. ROGERS, OF CHELSEA, MASSACHUSETTS, ASSIGNOR TO GEORGE W. DOWNING, OF PROVIDENCE, RHODE ISLAND.

IMPROVEMENT IN ORNAMENTING FURNITURE.

Specification forming part of Letters Patent No. 124,630, dated March 12, 1872.

SPECIFICATION.

I, JAMES E. ROGERS, of Chelsea, in the county of Suffolk and State of Massachusetts, have invented certain Improvements in the Ornamentation of Furniture, of which the following is a specification:

The drawing represents an elevation of the foot-board of a bedstead, to which my invention is applied.

The object of this invention is to produce a cheap and efficient method of ornamenting articles of furniture, &c., in imitation of inlaid work, or otherwise; and it consists in the application of lithographed or otherwise ornamented veneers to such articles, as will hereinafter more fully appear.

In the drawing, A represents the foot-board of a bedstead, provided with panels, in which are affixed correspondingly-shaped sheets of veneering, B, which are ornamented in any desired design by lithographed veneer. The veneering B is attached to the furniture in the usual manner, and may be cut in sheets of any desired size and shape, thus affording an easy

as well as cheap method of ornamenting any article of furniture, &c.

The advantage of employing lithography as the means of ornamenting the veneering, as above, is the facility with which it can be made to imitate inlaid work.

I am not aware that lithographing has been accomplished directly on wood heretofore; and as a method of ornamentation on this material it possesses marked advantages over decalcomanie and other transferring methods.

Having thus fully described my invention, what I claim as new, and desire to secure by Letters Patent, is—

The method of ornamenting furniture, &c., by means of lithographed veneering, substantially as described.

In testimony whereof I have signed my name to this specification in the presence of two subscribing witnesses.

JAMES E. ROGERS.
